UNITED STATES PATENT OFFICE

2,459,893

ABRADING DEVICE

Walter P. Peterson, Chicago, Ill.

Application May 27, 1946, Serial No. 672,621

2 Claims. (Cl. 51—187)

1

This invention relates to abrading devices or sanders which are adapted for various purposes and commonly used by carpenters and others as a hand tool for smoothing or finishing cabinet work or other surfaces. Devices of this kind are well known and their uses generally understood, the present invention being an improvement in the construction and arrangement of parts of one of such sanders now in use.

The objects of this invention are to provide an improved abrading device of simple and durable construction having novel or improved means for permitting the insertion of the abrading material and adjustment of the same; to provide an improved pivotal connection for the shoe and hood of an abrading device; and to provide such other novel features and improvements as will be described more fully hereinafter.

In the accompanying drawings illustrating this invention,

Fig. 1 is a plan view;

Fig. 2 is a side view showing the device in operative or adjusted position;

Fig. 3 is a longitudinal sectional view showing the abrasive strip or web fastened in position;

Fig. 4 is a similar view showing the parts extended or adjusted to permit the insertion or removal of the abrading strip;

Fig. 5 is a sectional view taken substantially on the line 5—5 of Fig. 2;

Fig. 6 is a sectional view taken substantially on the line 6—6 of Fig. 2; and

Figs. 7 and 8 are details of a combined hinge and clamping member.

A hood or upper body member 10 is shaped substantially as shown so that it may be conveniently grasped by the hand for operating the tool. It is preferably channel-shaped in cross section with a top 11 and sides or flanges 12. The sides are cut away adjacent to one end as shown at 36 to provide a transverse opening for the roll comprising the sanding strip 14. The top 11 is curved adjacent to one end and terminates in a clamping edge 13. The opposite end of the hood is somewhat reduced in width and formed as shown to provide a clamping portion or rib 15 with an adjacent groove 16.

The frame member or shoe 17 is of substantially channel-shaped cross section and of approximately the same length as the body member 10. One end of the shoe is curved upwardly as shown at 18 with its edge 19 opposed to the clamping edge 13.

A combined hinge and clamping member 20 of substantially semi-circular shape as shown in Fig. 4. In order to do this, the free end of the

2

Fig. 7 fits in the curved end portion 18 and is spot welded or otherwise secured thereto. It may be further held and braced by a tongue 21 which is struck up out of the flat portion of the shoe and is spot welded thereto at 22. The outer edge of the clamping member 20 has a flange 22 that fits over the edge 19 and coacts with the clamping edge 13 for holding the strip 14 in adjusted positions. The clamping member 20 has a pair of ears 23 that extend inwardly and are pivoted to the sides 12 by means of pivots or rivets 24, thus forming a hinged connection between the hood and the shoe. A form of spring rivets or fasteners known as "cinch fasteners" is convenient for use as such pivots.

The ends of the transverse opening which receives the roll of abrasive material 14 are closed by discs or cover plates 25 which are united by an integrally formed cross bar 26 and which have rearwardly extending ears 27 with holes for receiving the cinch fasteners 24. This arrangement is such that by lifting up on the cross piece 26, the cover plates 25 may be swung out of register with the opening, thus permitting the easy insertion of the roll. It will also be noted that the cinch fasteners serve as double pivots namely for the hood and for the cover discs.

The opposite end of the shoe 17 is bent upwardly at a substantially right angle and has an opening 28 through which the projection 15 extends. The upper edge 29 of this opening coacts with the groove 16 for clamping the end of the abrasive strip. A stiff spring 30 is interposed between the outer or free ends of the hood and shoe and tends to hold the lip 15 in clamping engagement with the coacting edge or clamping member 29. The lower end of the spring 30 is held in position by projections or ears 31 which are struck up from the surface of the shoe 17 leaving a hole 32.

The shoe 17 is provided with a block or strip 33 of resilient material such as rubber, or the like. This block extends somewhat around the ends of the shoe and is held in engagement therewith by integrally formed buttons 34 and 35 which project up through the holes or openings in the top of the shoe and fit closely therein. The strip of abrasive material is supplied in the form of a roll which is inserted in the transverse opening 28 and one end of the strip extends out between the clamping members 13 and 22 and then passes around the lower face of the resilient backing 33 and up through the opening 28 between the clamping members 15 and 29 as best shown in Fig. 4. In order to do this, the free end of the

hood is pressed downwardly as shown in Fig. 4 which causes the other end of the hood to swing up on the pivots 24 thereby moving the clamping edge 13 away from the flange 22 and leaving a sufficient opening for passing the strip therethrough. The free end is readily inserted and drawn tight so that when the hood is released, the spring holds the strip in sanding position as shown in Figs. 2 and 3. This arrangement of the pivot or fulcrum at a substantial distance from the clamping edge 13 comprises one of the important improvements in the present invention as it permits the roll to be more readily inserted and the strip properly adjusted for use. After the roll is inserted, it is held against lateral movement by the cover discs 25 which are swung down as shown in Fig. 2.

Having thus described my invention, what I claim is:

1. An abrading device, consisting of an elongated frame member curved at one end and bent at a substantially right angle at the opposite end, a combined hinge and clamping member secured to the curved end and having an outwardly projecting flange and also having inwardly projecting ears, a cover member pivotally connected to said ears and having a clamping edge opposed to said flange said pivotal connection being at a substantial distance from the clamping edge whereby the clamp may be readily opened a sufficient distance for the easy insertion and adjustment of the abrasive strip to be used in the device, said cover member having a clamping projection extending through an opening in the angularly turned end of the frame member and coacting therewith to form a clamp, and a spring between the frame member and the cover member tending to hold the clamping devices in clamping positions.

2. In a device of the character set forth, the

combination of a channel-shaped frame member having one end curved upwardly, a substantially semi-circular clamping member rigidly secured in the curved portion and providing a transverse jaw at the outer end, said clamping member also having inwardly extending ears, a handle member pivotally connected with said ears and having a transverse clamping edge adapted to coact with the first named clamping member, said handle member having a transverse grooved portion at its free end extending through an opening in the free end of the frame member to form clamping means, a compression spring between the free ends of said members tending to press them apart, and a pad of resilient material mounted in the frame member and extending longitudinally thereof, the arrangement being such that the spring tends to hold both of the clamping members in closed position but may be compressed to open both of said clamping members whereby a roll of abrasive strip material may be inserted in the first named clamping member with its end extending out between the first named clamping members and around the pad and then brought into engagement with the clamp at the free end of said members whereby the strip will be clamped in two places when the spring returns to normal position.
